CHECK WRITER

Edgar Ellsworth Phinney, West Orange, N. J.,
assignor to Defiance Manufacturing Corporation,
Orange, N. J., a corporation of New York

Application May 10, 1934, Serial No. 724,893

5 Claims. (Cl. 101—93)

The invention has relation to checkwriters, one feature of the invention providing improved means whereby the insertion of a check to be printed will control the operation of the machine. According to another feature of the invention control devices are adapted to provide for the convenient operation of the machine in conjunction with an accumulating and listing mechanism which may also be separately operated.

The invention consists in the novel construction and combination of parts as set forth in the appended claims.

In the accompanying drawings illustrating the invention:

Fig. 1 is a right side elevation of the machine with the accumulator and lister partly broken away.

Fig. 2 is a detail section through the accumulating and listing unit, showing the value setting means.

Fig. 3 is a similar view showing the means for setting the check printing type, etc.

Fig. 4 is a right side elevation of the accumulating and listing unit, with the casing broken away.

Fig. 5 is a plan view of the platen, check feed and motor unit.

Fig. 6 is a section taken on line 6—6, of Fig. 5.

Fig. 7 is a section taken on line 7—7, of Fig. 5.

Fig. 8 is a section taken on line 8—8, of Fig. 5.

Fig. 9 is a wiring diagram of the motor and solenoid circuits.

The machine may be considered as consisting of three units, best seen in Fig. 1, these comprising an accumulating and listing unit 1, attached at 2 to a type wheel unit 3, said type wheel unit being pivotally connected at 4 with a platen, check feed and motor unit 5.

The accumulating and listing unit 1 consists preferably of a complete adding and listing mechanism, being shown as corresponding to the disclosure of U. S. Patent 1,932,013, issued to Loring P. Crosman on October 24, 1933.

In accordance with this disclosure reciprocal movement of a shaft 6 (Figs. 1 and 2) will rock a frame upon which are mounted a series of dogs 7, so that said dogs tend to move out of engagement with studs 8 of a series of setting levers 9, allowing said levers to swing, under the influence of springs 10, until stops 11, carried by said levers engage the stems of depressed digit keys 12, which serve to limit the movement of the levers in accordance with the value to be set up. This serves to set type 13, carried by type bars 14 secured to the levers 9, into correct printing position, spring hammers 17 being released in well known manner to effect printing on a suitable record tape. Suitable pinions of one or more accumulators 15 are brought into mesh with

segments 16 of the levers 9, so that the return movement of the frame carrying the dogs 7 in returning the levers 9 to normal position, will register the set values in the accumulators 15. At the conclusion of a series of operations the accumulators 15 may be cleared and the totals accumulated thereon printed on the record tape, in well known manner.

During the setting of the levers 9, the values set in the keys 12 will also be transferred to type 10 wheels 18 (Fig. 3) in the following manner: A shaft 19 is reciprocated synchronously with the accumulator unit shaft 6, by means of a bell crank lever 32, connected with shaft 6 by a link 30 and with shaft 19 by a link 31, lever 32 being connected with a source of power through push rod 34, as hereinafter set forth.

Clockwise movement imparted to shaft 19 (Figs. 1 and 3) will, through cam 20 and lever 21, move a series of dogs 22, engaging racks 23, so that said racks are free to be moved rearwardly by their springs 24. The rear ends of racks 23 are provided each with a series of graduated stop faces 25, adapted to contact with extensions 26 of the type bars 14. The cam 20 provides for a slight dwell before the rearward movement of racks 23 is started, this dwell giving the upward movement of type bars 14 a slight lead, whereby the contacting portions of the extensions 26, being raised with the type bars, are brought successively into their different digital value positions, and the racks 23 are prevented from contact with the extensions 26 until the type bars have come to rest in their selected positions. The graduated faces 25 provide for the adjustment of racks 23 in accordance with the set positions of the related type bars 14. Rearward movement of the racks 23 to adjusted position will, through engagement with suitable pinions of the wheels 18, set the appropriate type in position to be engaged by the check printing platen 27.

The bottoms of the extensions 26 are provided with offset angularly bent lugs 28, forming the contact portions of the extensions, and also serving, by engagement with plates 29 to prevent rearward displacement of the type bars and extensions when contacted by the racks 23. The plates 29 are preferably formed from a single strip of metal, slotted to permit the passage of racks 23 and to provide guides for the extensions 26, as shown in Fig. 3.

The above-described arrangement, whereby the accumulating and listing mechanism and the type wheel mechanism is separately adjusted in accordance with the key setting, is of advantage in that the extra load of the type wheels and racks is removed from the setting levers 9 of the lister, avoiding undue strengthening of the springs 10. It is also of advantage because in-

- dependent movement of the type wheels 18 is necessary if the customary devices (not described) for setting up arbitrary symbols on the type wheels are employed, since this entails yieldable connections between the racks 23 and the levers 9, occasioning spring return movement of the racks into contact with said levers (or their type bars). According to the present construction, any such impact is taken up by the plates 29.
- As stated, the two rock shafts 6 and 19 are connected through crank arms and links 30, 31 (Fig. 1), with opposite arms of a bell crank lever 32, fulcrumed at 33 upon the frame of unit 3. This bell crank lever has connection with a push rod 34, having pin and slot connection 35 with the frame of unit 5, and being provided with a transverse slot engaged by a roller 36, mounted upon a crank arm forming part of a driven clutch element 37, engageable with a driving element 38, mounted upon shaft 39, having direct gearing connection with the motor 40.
- The clutch member 37 is provided with a spring pawl 41, normally held disengaged from the teeth of member 38 by a latch 42 pivoted to the framing at 43, and movable to releasing position by means of a rod 44. The latch 42 is also provided with an insulated roller, acting to close the contacts of a circuit breaker 45, when the latch is released. Circuit breaker 45 is interposed in the motor circuit, and serves to start the motor when the clutch is engaged, and to maintain the circuit through the motor until the clutch is released, which release will be effected at the end of a single cycle of the clutch elements, by contact of a pin 46 with a tooth 47 of latch 42, the latch being thereby forced back into position to be engaged by pawl 41, in the rotation of the parts, further rotation serving to lift the engaged pawl out of contact with the teeth of member 38.
- The clutch may be engaged by operation of a motor key 48 (Fig. 4) of the lister, or by the means hereinafter described. Key 48 upon depression rocks a latch 49, releasing a spring impelled lever 50, connected by a push rod 51 with one arm of a bell crank lever 52 (Figs. 1 and 8, rod 1 being located directly behind rod 81 in Fig. 1). The other arm of lever 52 is connected with the clutch releasing rod 44.
- Operation of the clutch by key 48 (as will be seen) does not effect printing of the check, and the setting movements of the type wheels 18 will be idle. In other words, the key 48 is operated in connection with the adding and listing devices only, and will serve to illustrate how totals may be printed, by means of the well known total taking mechanism of the lister, and through the tripping of latch 49, without effecting a printing operation of the check writing mechanism.
- The units 1 and 3 are designed to be raised by movement about pivot 4, in order to give access to the type ribbon 57, (Fig. 3) etc. a latch 58 (Fig. 1) being provided to hold the units 3 and 5 in their normal operating positions. In order that the machine shall not be operated unless the units 1 and 3 are in correct position, a circuit breaker 59 (Fig. 4) is interposed in the motor circuit, one contact of this circuit breaker being located in unit 1 and the other contact in unit 3. Circuit breaker 59 may also be broken when the machine is locked against operation, in which case a bolt 60, is moved to the right, out of the position illustrated in Fig. 4, allowing the spring contact arms of the circuit breaker to move the pivoted member 61 and separate. Upon locking of the machine bolt 60 will rock a lever

62, link 63 and dog 64, bringing the dog into the path of movement of the latch 49, so that key 48 will be locked and lever 50 cannot be released.

The platen 27 is mounted on a frame 53 (Figs. 3 and 5), said frame being pivoted at 54 in the framing of the unit 5. A cam 55, mounted on shaft 39, moves the platen from the position shown in Fig. 3 into contact with the type of the wheels 18. Time is given for this printing to be effected before the type wheels are restored to normal position, by means of an arcuate recess 56 (Fig. 1) in the push rod 34, along the wall of which recess the crank roller 36 will have idle movement before entering the narrow portion of the slot, to rock the shaft counter-clockwise to its original position.

Means are provided whereby the insertion of a check to be printed within a guide-way 65 and into contact with feed rolls 66 (Figs. 5, 6 and 7) will serve to start the motor and feed the check into position to be printed. For this purpose a lever 67 projects into the path of the inserted check, the advance of the check (manually or otherwise fed) serving to rock the lever, which has a crank extension, provided with an insulated roller, and thereby to close the contact elements of a circuit breaker 68. This circuit breaker is inserted in a wiring circuit hereinafter more fully described, serving when closed to start the motor and thereby, through the gearing 69 (Fig. 6) shaft 70 and pinions 71, driving the connected shafts 72, 73, 74, (Fig. 5) on the latter of which the feed roll 66 is mounted.

This roll will advance the check along the guide-way 65 until it comes in contact with the end of a lever 75, having a universal joint connection 76 (Figs. 5 and 6) with the frame of unit 5. Lever 75 is provided with an insulated roller which, when the lever is displaced horizontally by the fed check, will act to close the contacts of a circuit breaker 77, interposed in a circuit in which is also interposed a solenoid 78 (Fig. 4). Solenoid 78 serves to adjust the check printing mechanism into operative position and to engage the clutch 41, as follows:

The solenoid being energized, will rock lever 79 about fulcrum 80, moving push rod 81 against a latch 82 (Figs. 1, 5 and 8) and disengaging said latch from the end of a spring pressed rod 83. Rod 83 being released will move to the right under the influence of its spring 84, carrying therewith the rear end of a lever 85 intermediate fulcrumed upon the platen carrying frame 53, and carrying the forward end of said lever into position above the printing cam 55 (Figs. 3 and 5). In this position of the parts, the forward end of lever 85 will serve as a filler between cam 55 and frame 53, so that upon rotation of the cam with its shaft 39, the platen 27 will be forced up against the type.

Rod 83, moving under the influence of its spring as above-described, will also contact with a bell crank lever 86 (Figs. 1 and 5) the opposite arm of said lever engaging a collar 87 on the clutch engaging rod 44, moving said rod rearward and releasing the clutch pawl 41. The amount now set on the keys 12 will be accumulated, listed and printed upon the check.

After the printing is effected, the check will be released from contact with the lever 75 and will be fed out of the machine, this being accomplished as follows:

While the check is lying against lever 75, it is still in contact with the feed roll 66, this roll contacting with the check lightly and not acting

to displace the check so long as lever 78 remains in its path. One edge of the check remains in engagement with an extension of the guide 65, and this has proved sufficient to prevent buckling of the check at this time. However, the printing being accomplished, a cam 88 (Fig. 6) mounted on shaft 39, will engage one end of a pawl 89, forcing the other horizontally bent end of said pawl against the lever 78, and thereby pulling the free end of said lever downwardly out of the path of movement of the check. Thereupon the check will feed forwardly into contact with feed roll 90, by which roll it will be fed out of the machine.

15 After the printing of the check has been completed, the lever 85 will be returned to its normal position, with the forward end thereof out of register with the cam 55, by means of a restoring cam 91 (Figs. 3 and 5) mounted on shaft 39, said cam acting upon a lever 92 having an arm engaging a roller 83, of a restoring lever 94 (Fig. 8), a second roller mounted on lever 94 engaging a collar 85 secured to the rod 82, so that movement of the lever 92 by cam 91 will restore rod 83 to normal position, whereupon latch 82 will be moved into the path of said rod by its spring 86 (Fig. 1), this movement not being resisted by solenoid 78 because of the breaking of the current through said solenoid by the previous opening of contact 71.

20 The disengagement of clutch 41 and the breaking of the contact 45 at the end of the cycle of movement of shaft 39 has been previously described, this action completing the operation of the machine.

25 The various controls operated by the check in its passage through the machine may be traced in the wiring diagram (Fig. 9). In this diagram 97 indicates the contact points whereby electrical connection is made with the service line. Circuit breaker 59 remains closed as long as the machine stands in condition for operation, and thus forms a master switch. Manual adjustment of the check to be printed serving to close the circuit breaker 68, current will flow through the motor 40, and the check feed devices will be operated. The check being fed until it causes closing of the circuit breaker 71, current will be established through the solenoid 78, which solenoid will effect the closing of the one cycle circuit breaker 45 and the engagement of the clutch. The printing will now be effected and the check fed out of the machine, during which feeding movement the circuit breaker 68 will be released. However, circuit breaker 45 is still held closed, permitting the feeding out of the check and the restoration of the various mechanisms, before the circuit through the motor is finally broken.

30 In use, the amount for which a check is to be made out is entered by depression of the appropriate keys 12, and a blank check is fed to the guide 65, whereupon the check will be printed and discharged, and the amount will be listed and accumulated.

35 To list without printing a check, an amount may be set on the keys 12 and listed by depression of key 48, which key does not shift the lever 85 to check printing position.

40 Totals, either of checks or other accumulated amounts, may be printed upon the list sheet by the well known mechanism for this purpose, which mechanism will involve an operation of the list-

ing mechanism similar to that effected by key 48.

I claim:

1. In a checkwriter having an electric motor, circuit devices including a circuit breaker adapted to connect said motor with a source of power, printing means, drive connections including a clutch between the printing means and the motor, and check feed devices driven directly from said motor; a guide-way, means adjacent said guide-way and operable by contact with a check inserted therein to close the circuit breaker and thereby start the feed, and means adjacent said guide-way and operable by contact with a fed check to engage the clutch and thereby effect printing. 10

15 2. In a checkwriter having an electric motor, circuit devices including a circuit breaker adapted to connect said motor with a source of power, printing means, drive connections including a clutch between the printing means and the motor, and check feed devices driven directly from said motor; a guide-way, means adjacent said guide-way and operable by contact with a check inserted therein to close the circuit breaker and thereby start the feed, secondary circuit devices 20 for said motor in parallel with the first-named circuit devices and including a circuit breaker, and operating connections between the clutch and the last-named circuit breaker.

25 3. In a checkwriter having an electric motor, circuit devices including a circuit breaker adapted to connect said motor with a source of power, printing means, drive connections including a one-cycle clutch between the printing means and the motor, and check feed devices driven directly 30 from said motor; a guide-way, means adjacent said guide-way and operable by contact with a check inserted therein to close the circuit breaker and thereby start the feed, means including a solenoid operable to engage the clutch and thereby effect printing, means adjacent said guide-way and operable by contact with a fed check to energize said solenoid, secondary circuit devices 35 for said motor in parallel with the first-named circuit devices and including a circuit breaker, and operating connections between the clutch and the last-named circuit breaker. 40

4. In a checkwriter having accumulating and listing mechanism, printing mechanism, a motor, drive connections including a clutch between the motor and the accumulating and listing mechanism, and normally disabled operating means between the clutch and the printing mechanism; a guide-way, means adjacent said guide-way and operable by contact with a check moving therein to render the printing operation means effective, and means operable by the check operated means to engage the clutch. 50

5. In a checkwriter having accumulating and listing mechanism, printing mechanism, a motor, drive connections including a clutch between the motor and the accumulating and listing mechanism, and normally disabled operating means between the clutch and the printing mechanism; a guide-way, normally restrained spring actuated 55 means for rendering the printing operation means effective, means adjacent said guide-way and operable by contact with a check moving therein to release the spring actuated means, and means operable by the spring actuated means to engage the clutch. 70

EDGAR ELLSWORTH PHINNEY.
